DECORATIVE CANDLE SUPPORT

Jessie Robinson Walker, Los Angeles, Calif.

Application October 11, 1946, Serial No. 702,726

1 Claim. (Cl. 67—23)

1

The present invention relates to a candle support which at the same time serves as a decoration.

An object of the present invention is to provide an improved candle support which serves to maintain a candle in an upright position even though the candle stick is subjected to temperatures which otherwise would cause the candle stick to bend and assume an unsightly appearance.

Another object of the present invention is to provide an improved candle support which may be used over and over again and which when in use adds a decorative note to the surroundings.

The features of the present invention which are believed to be novel are set forth with particularity in the appended claim. This invention itself, both as to its organization and manner of operation, together with further objects and advantages thereof, may be best understood by reference to the following description taken in connection with the accompanying drawings in which:

Figure 1 shows a decorative candle support embodying the present invention mounted on a candle stick.

Figure 2 is a sectional view taken substantially on the line 2—2 of Figure 1.

Figure 3 is a sectional view taken substantially on line 3—3 of Figure 1.

Figure 4 is a plan view of a portion of the candle support before it is formed into the shape shown in Figure 1.

Figure 5 is a view in end elevation of the member shown in Figure 4 and the dotted lines thereon indicate the manner in which the member in full lines is subsequently formed to produce a portion of the structure shown in Figure 1.

Figure 6 is a view of another candle support embodying the present invention but for the sake of showing more clearly the structure thereof, some of the flower decorations normally thereon, are removed.

Figure 7 is a sectional view taken substantially on line 7—7 of Figure 6.

The decorative candle support with the ornamentation and wax drip catcher thereon may be of plastic material, glass, carved wood, cast or wrought metal, or composition material but I prefer at this time to make the support entirely of earthenware material such as clay which is suitably fired in elevated temperatures preferably with glaze material thereon; although, the entire article, if desired, may be fired without initially applying glaze material thereto. Also,

2

such earthenware material may include porcelain and china.

Figure 6 shows the preferred embodiment of the present invention with some of the flower decorations removed to more clearly show the basic supporting structure. In Figure 6, the candle support having the general reference numeral 10, comprises: a hollow cylindrical member 11 with openings 12, 13 extending through, and with flower decorations 14, a candle drip catcher 15 integrally formed therewith. It is within the scope of the present invention to use other types of decorations as well, and such decorations may be in the nature of representations of fruit, vegetables, fish, birds, animals etc.

The inner diameter of the cylindrical member 11 is substantially equal to the diameter of the wax candle upon which it is mounted, the mounting being performed by threading the candle therethrough, so that the support 10 is positioned at the lower end of the candle near the candle stick 16 and preferably with the lower end 17 in abutment with the candlestick 16 whereby at least some of the weight of the support 10 is carried directly by the candlestick 16.

Of importance is the fact, that the support 10 maintains the shape of the wax candle even though the wax of the candle becomes soft under the influence of heat produced either by burning of the candle, by sunlight or by ambient temperatures. For this purpose, the support 10 is made relatively long whereby a relatively long length of the candle may be braced and the support is made of a material which may be in the class enumerated above including clay which maintains its form under all conditions, and especially when it is subjected to immediate contact with molten wax. One advantage of the use of fired clay or other non-burnable or non-scorchable material, as contemplated in some of the different embodiments of the present invention is that when perchance, the candle is allowed to burn sufficiently low to cause immediate contact of the candle flame with the support 10, no permanent damage results to the support. Under such conditions, the candle support 10 is not damaged and may be used over and over again on different candles after the preceding candle is expended.

This preformed structure shown in Figure 4 is then made into a hollow cylindrical candle supporting structure by forming it into the shape indicated in dotted lines in Figure 5 and by kneading the abutting ends of the plastic material together at the seam 25 so that eventually

there is no seam 25 in the completed structure. Thereafter, clay flowers 26, 27 or other decorations in the form of so-called "slip" material are affixed to the circular strips 21, 22 and then the composite structure is "fired" at a relatively high temperature to produce the finished article of decorative appearance having the capability of being used over and over again to maintain candles in upright position.

Although the support shown in Figure 6 has openings 12, 13 in the wall thereof whereby a portion of the candle in the support 10 may be viewed to thereby provide a pleasing contrast in colors between the color of the candle and the color of the support 10, these openings 12, 13 15 may be omitted if desired. In any case, flower decorations 14 are formed integrally with the hollow cylindrical portion 11. These flower decorations 14 may be of the same size, type and appearance as existing natural flowers and in the gladiolus shown in Figure 6, the filaments thereof may comprise a cluster of straight pieces of wires 20, each having their inner end embedded in the material.

In order to prevent molten wax from a burning candle from running down over the decorative support, a wax drip catcher 15 may be integrally formed at the upper end of the cylindrical member 11. This wax catcher 15 is cup-shaped as indicated in Figure 7 and preferably the wall thereof is undulatory in nature to provide a pleasing appearance in harmony with the floral decorations.

The candle support may take other forms and shapes. In the arrangement shown in Figures 1 to 5, inclusive, the candle support is formed from a flat piece of plastic clay material cut as indicated in Figure 4 to provide two rectangular strips 21, 22 which are connected by the X-shaped lattice member 23.

Of course, if the support is made of the other materials enumerated above, this kneading proc-

ess need not be performed and the component parts of the support may be molded, cast, carved, wrought, formed or worked into final shape by other processes and the particular process described above is but one example of the manner in which the support may be made.

While the particular embodiments of the present invention have been shown and described, it will be obvious to those skilled in the art that changes and modifications may be made without departing from this invention in its broader aspects and, therefore, the aim in the appended claim is to cover all such changes and modifications as fall within the true spirit and scope of this invention.

I claim:

An article of manufacture consisting of spaced, rigid, integral, tubular sleeve-like members arranged to extend around and frictionally engage a candle extending therethrough and beyond both ends thereof, lattice-like rigid means extending between and integrally attached to said tubular members, said means being arranged to lie against the surface of the candle and uniting said tubular members into a rigid unitary structure adapted to stiffen the candle therein, and decorative means attached to the outer surface of said unitary structure.
